UNITED STATES PATENT OFFICE.

CHARLES WALES, OF NEW HAVEN, CONNECTICUT, ASSIGNOR TO THE WHITE ADDING MACHINE COMPANY, OF NEW HAVEN, CONNECTICUT, A CORPORATION OF CONNECTICUT.

CALCULATING-MACHINE.

1,206,059.

Specification of Letters Patent. Patented Nov. 28, 1916.

Application filed April 22, 1915. Serial No. 23,073.

To all whom it may concern:

Be it known that I, CHARLES WALES, a citizen of the United States, residing at New Haven, county of New Haven, State of Connecticut, have invented certain new and useful Improvements in Calculating-Machines, of which the following is a full, clear, and exact description.

My invention relates to calculating machines and has for its object to provide a machine which can be operated either by hand or by electric power, with means whereby the handle can be moved into and out of its normal operating position, and also with means whereby when the handle is in normal position the power circuit will be open.

It also has for its object to provide means for closing the power circuit when the handle is in its other position.

It also has for its object to provide a visual signal which shall indicate when the power circuit is open.

It also has for its object to provide means whereby the clutch-operating member is mechanically cut out of action when the motor circuit is open.

It also has for its object to provide means for holding the handle onto its shaft.

The following is a description of an embodiment of my invention, reference being had to the accompanying drawings, in which,—

Figure 1 is a side elevation of a calculating machine embodying my invention. Fig. 2 is an enlarged view of the handle upon the end of the shaft which it operates, and in normal operating position, looking from the rear (Fig. 1). Fig. 3 is a side view of Fig. 2. Fig. 4 is a detail of an abutment plate carried by the shaft on which the handle is placed. Fig. 5 is a perspective view of the inner end of the barrel of the handle.

Referring more particularly to the drawings, 1 is the near side frame of the operating mechanism of a calculating machine.

2 is the far side of the same.

3 is an electric motor mounted at the rear end of the machine, and having a shaft 4 extending between the frames 1 and 2 to suitable connections (not shown) for actuating the crank shaft 5.

6 is an abutment plate secured to the shaft 5. This plate is provided with an abutment face 7 with which the handle engages.

8 is the handle having a hollow barrel

9 which passes over the end of the shaft 5. It is provided on its inner end with a projection 10 which, when the handle is in position, engages the lower face 7 of the abutment on the plate 6. With the parts in this position when the handle is pulled forward the plate 6 and shaft 5 are rotated in a counter clockwise direction. A handle is provided with a cutaway portion or recess 11 and with a groove or socket 12 in line with the inner part thereof. It is also provided with a recess 13 having a square face for purposes hereinafter set forth.

Mounted on the abutment is a spring pawl 70 or detent consisting of a lever 14 carrying a detent wheel 15 having a flange 16 which fits the groove or socket 12 in the handle barrel. A spring 17 is connected to the lever 14 and the abutment plate 6, drawing the detent wheel 15 toward the shaft 5 and causing it to engage the groove or socket 12 in the handle barrel when the handle is in normal position. This holds the handle against endwise movement so that it cannot be removed 80 while in normal position. It also yields when the handle is thrown backward so as to prevent such backward throw from imparting a shock to the mechanism through the shaft 5. If, however, the handle is 85 moved to the position shown in Fig. 1 the flange 16 of the detent 15 rides up out of the socket or recess 12 whereupon the handle can be pulled off. In order to make it easy to put the handle on the recess or 90 cutaway portion 11 is provided. This is opposite the detent 15 when the handle is in the position shown in Fig. 1 being angularly in front of the groove or socket 12. In order to put the handle on it is held in the position shown in Fig. 1 and slipped on the shaft 5. Thereafter, when it is moved to normal position (Figs. 2 and 3) the detent wheel 15 is caused to rise up until it reaches and falls into its socket 12, at which time 100 the projection 10 engages the abutment 7. In order to prevent any undue strain from bending the detent plate 14 I provide a strain-resisting stud 18 which is secured to the lever 14 and passed through a slot 19 105 in the abutment plate 6. This stud is provided with an enlarged head which engages the inner surface of the abutment plate 6 and aids the lever 14 in resisting any strain due to an attempt to remove the handle 110 while in normal position.

In order to control the motor circuit

through the handle I provide a switch 20 from which lead the motor circuits 21, 22. 23 is the actuating lever of the switch having an "off" or open circuit position and an 5 "on" or closed circuit position. The operating lever revolves about the axis 24, and has a link 25 connected to it which in turn is connected to the arm 26 extending downwardly from the rod 27. The rod 27 is 10 provided with an adjusting turnbuckle 28 and is connected to the upper end of a rock arm 29 fixed on the rock shaft 29² at its farther end. On the near end of this shaft 29² and in the same angular position on the 15 shaft is also pivoted a rock arm 29 of same shape and size as 29'. To the arm 29 is connected the rod 30 whose forward end rests on the barrel 9 of the handle and rides thereon, its length being such that when 20 the handle is in normal position the end of the rod falls into the recess 13. When the handle is moved backward to the position shown in full lines in Fig. 1 the straight face of the notch forces the rod 30 and with 25 it the rock arms 29 29' backward. This results in pulling the rod 27 to the position shown in Fig. 1 and moves the switch lever 23 and switch to "on" position. The rock arm 29 is provided with a retracting spring 30 31 the forward end of which is connected to the stationary frame of the machine. When the handle is moved upward to normal position this spring moves the rock 35 arms 29 29' and rod 27 forward so as to throw the switch lever to "off" position. When the handle is in normal position with the machine at rest the handle is in the position shown in dotted lines. In this position it is clearly visible and constitutes a visual 40 signal or indicator showing that the motor circuit is open. When it is not in this position the fact that the motor circuit is closed can be perceived at a distance. This visual indicator reduces the liability of having the 45 power circuit closed when the machine is not in use and inasmuch as motors in this type of machine run continuously during the whole period when the machine is in use as a power driven machine, and until cut out by a voluntary movement of the attendant, this visual indication results in considerable saving of expense and wearing of the parts. 50

32 is a plate on the keyboard the depression of which operatively connects the motor shaft to the operating mechanism of the machine. This connecting mechanism is described in my pending application, Serial No. 874,975, filed December 1, 1914, and is actuated by the lever 41, so that when that 55 lever is depressed the motor shaft drives the calculating mechanism. The plate 32 is provided with a depending arm the lower end of which is normally at a point just above the end 34 of a rod 35 connected to the rock arm 29. This end is provided with a cam

slot 36 in which is a pin 37 projecting laterally from the end of the lever 41. When the rod 35 is in that position shown in Fig. 1 the pin 37 is in the lower horizontal end of the slot 36, and when the plate 32 is moved 70 downward the arm 33 engages the end 34 and, acting through it, forces the lever 41 down so as to connect up the motor to the mechanism. When however the rock arm 29 is moved forward upon being freed from 75 the control of the handle, the front end of the rod, thanks to the cam slot 36, moves to the lower position shown in dots in Fig. 1 so as to be out of the path of the arm 33 when actuated by the plate 32. From this 80 it results that the motor cannot be coupled by depressing the plate 32 if the handle of the machine is in normal position relative to its shaft 5, but can be if the handle is thrown back so as to throw the switch lever 85 23 to "on" position.

As will be evident, my invention permits of various modifications without departing from the spirit thereof or the scope of the appended claims.

What I claim is:

1. In a computing machine, the combination of a calculating mechanism, a motor and a handle for operating the same at different times, a switch controlling said motor and controlled by said handle so as to be in "off" position when said handle is in normal position. 90
2. In a computing machine, the combination of a calculating mechanism, a motor and a handle for operating the same at different times, a switch controlling said motor, connections between said handle and said switch controlled by said handle so as to open said switch when said handle is in normal position and close said switch when said handle is in abnormal position. 100
3. In a computing machine, the combination of a calculating mechanism, a motor and a handle for operating the same at different times, a switch controlling said motor and controlled by said handle so as to be in "off" position when said handle is in normal position, a trip plate, motor connecting means actuated thereby, and means for preventing said trip plate from actuating said means when said handle is in normal operating position. 110
4. In a computing machine, the combination of a calculating mechanism, a motor and a handle for operating the same at different times, a switch controlling said motor and controlled by said handle so as to be in "off" position when said handle is in normal position, a trip plate, motor connecting means actuated thereby, and means for preventing said trip plate from actuating said means when said handle is in normal operating position, said means consisting of a member controlled by said handle and 120
5. In a computing machine, the combination of a calculating mechanism, a motor and a handle for operating the same at different times, a switch controlling said motor and controlled by said handle so as to be in "off" position when said handle is in normal position, a trip plate, motor connecting means actuated thereby, and means for preventing said trip plate from actuating said means when said handle is in normal operating position, said means consisting of a member controlled by said handle and 125
6. In a computing machine, the combination of a calculating mechanism, a motor and a handle for operating the same at different times, a switch controlling said motor and controlled by said handle so as to be in "off" position when said handle is in normal position, a trip plate, motor connecting means actuated thereby, and means for preventing said trip plate from actuating said means when said handle is in normal operating position, said means consisting of a member controlled by said handle and 130

moved thereby into and out of operative position relatively to said trip plate.

5. In a calculating machine, the combination of an actuating shaft, a removable handle provided with a hollow barrel fitting on the outside of said shaft, a pawl carried by said shaft and spring pressed toward said barrel, said barrel having a socket receiving said pawl when said handle is in operative 10 position, and a cutaway portion in front of said socket and extending from the end of said barrel to a transverse plane in which said socket lies.

6. In a calculating machine a shaft, an 15 abutment carried thereby, a handle on said shaft for manually operating the same, a roller pawl connected to said shaft and movable toward and away from said shaft, said handle having a circumferential groove with 20 which said roller pawl engages, and also having a projection engaging said abutment fixed to said shaft.

7. In a calculating machine a shaft, an abutment carried thereby, a handle on said

shaft for manually operating the same, a 25 roller pawl connected to said shaft and movable toward and away from said shaft, said handle having a circumferential groove with which said roller pawl engages, and also having a projection engaging said abutment 30 fixed to said shaft, said handle having also a recess in its inner end whose outer end is in line with said groove, said recess being in front of said groove.

8. In a motor driven calculating machine, 35 the combination of a calculating machine and electric motor, and electric circuit therefor, a manually operated handle for said calculating machine, and means controlled by the handle for breaking said electric cir- 40 cuit when the handle is in normal position and for completing said electric circuit when the handle is in an inoperative position.

CHARLES WALES.
